[57] CLAIM

The ornamental design for a side mount for telescopic sight, as shown and described.

DESCRIPTION

FIG. 1 is a perspective view of a side mount for a telescopic sight showing my design;

FIG. 2 is a view as seen from the right side of FIG. 1;

FIG. 3 is a view as seen from the left side of FIG. 1;

FIG. 4 is a view as seen from the left end of FIG. 2;

FIG. 5 is a view as seen from the right end of FIG. 2;

FIG. 6 is a top view of my new design; and

FIG. 7 is a bottom view thereof.
